UNITED STATES PATENT OFFICE.

CLARA L. MEAD, OF RAHWAY, NEW JERSEY, ASSIGNOR TO DENNISON MANUFACTURING CO.,
OF BOSTON, MASSACHUSETTS, A CORPORATION OF MASSACHUSETTS.

DESIGN FOR DECORATIVE PAPER.

No. 39,295.

Specification for Design.

Patented May 5, 1908.

Application filed March 14, 1908. Serial No. 421,270. Term of patent 7 years.

To all whom it may concern:

Be it known that I, CLARA L. MEAD, a citizen of the United States, residing at Rahway, in the county of Union and State of New Jersey, have invented a new, original, and ornamental Design for Decorative Paper, of which the following is the specification, reference being had to the accompanying drawing, forming part thereof.

The figure is a front view of the decorative paper, showing my new design.

I claim:

The ornamental design for decorative paper, as shown.

CLARA L. MEAD.
